UNITED STATES PATENT OFFICE

KARL KREUTZER, OF NUERMBERG, GERMANY, ASSIGNOR TO FIRM J. S. STAEDTLER, OF NUERMBERG, GERMANY

DESIGN FOR A DRAWING PENCIL

Application filed February 7, 1931, Serial No. 38,578, and in Germany September 2, 1930. Term of patent 7 years.

To all whom it may concern:

Be it known that I, KARL KREUTZER, a citizen of Germany, residing at Nuremberg, (Bavaria), Germany, have invented a new, original, and ornamental Design for a Drawing Pencil, of which the following is a specification, reference being had to the accompanying drawings, forming part thereof.

Fig. 1 is a front view of a drawing pencil showing my design; Fig. 2 is an end view; and Fig. 3 is a rear view.

The design consists in parallel stripes differing in colour from the pencil material,

these stripes being uniformly distributed around the circumference of the pencil and extending over the greater part of its length, the portion not provided with stripes being plain and separated from the striped portion by a circular band extending entirely around the pencil.

I claim:—

The ornamental design for a drawing pencil, as shown and described.

In testimony whereof I affix my signature.

KARL KREUTZER.
